UNITED STATES PATENT OFFICE.

CHARLES ALEXANDER BAILEY, OF CROMWELL, CONNECTICUT.

TOY PISTOL.

1,251,462.

Specification of Letters Patent.

Patented Jan. 1, 1918.

Application filed May 12, 1917. Serial No. 168,246.

To all whom it may concern:

Be it known that I, CHARLES A. BAILEY, a citizen of the United States, residing at Cromwell, in the county of Middlesex and State of Connecticut, have invented certain new and useful Improvements in Toy Pistols, of which the following is a specification.

The object of my improvement is simplicity and economy in construction.

In the accompanying drawing:—

Figure 1 is a side elevation of a toy-pistol embodying my invention.

Fig. 2 is a reverse view of the same.

Fig. 3 is a sectional view on an enlarged scale on the line $\alpha\alpha$ of Fig. 1.

Fig. 4 is a view corresponding to Fig. 1 of a modification of a toy-pistol.

Fig. 5 is a reverse view of the same.

My improved toy-pistol comprises a frame structure 10 in the form of a single casting, a hammer member 11 operatively housed in the said structure, and also a spring 12.

The frame structure 10 comprises a bar 13 at one end, a handle 14 at the other end, and intermediate the said ends there is a structure comprising on the upper side the anvil 15, the guard 16 on the lower side, in the form of a loop, and between the anvil 15 and the guard 16 is the body 17 in which is positioned the hammer member 11.

The handle 14 is recessed or paneled on both sides, and in the panel 18 on the left side, shown in Fig. 1, is housed the body portion of the spring 12.

The spring 12 consists of a single piece of round wire and is curved from end to end to conform generally to the handle 14 and the adjacent part of the body 17.

The lower rib or flange 19 at the butt of the handle 14 that incloses the panel 18 is provided on the inner side with an inwardly directed lug 20 that serves as a backing for the lower end 21 of the spring 12.

Positioned in the panel 18, adjacent the lug 20, is an outstanding lug 22 that is separated from the general level of the opposed face of the panel 18 by a space in which is housed the power body portion of the spring 12.

Actually, the portion of the handle 14 opposed to the outstanding lug 22 is cut away, leaving an open gap 23 in the handle 14, back of the lug 22, which is bridged by the part 24 of the spring 12 that is back of the lug 22.

Thus the spring 12 is tucked in as it were

between the outstanding and overhanging lug 22 and the cut-out body wall or web portion 25 of the handle 14 and is free to move to a limited extent in the plane of the web 25, to correspond to the different positions of the spring for the cocked and the fired positions of the hammer member 11.

The spring 12 extends from the stop lug 20, along the web 25, under the lug 22, as mentioned, and terminates at the upper or inner end within the body 17, the extreme end portion 26 being housed in a recess 27 in the hammer member 11.

The housing 17 is of skeleton construction, comprising, as applied to Fig. 1, a rear wall portion and a front wall portion in spaced relation, for operatively housing the hammer member 11, and having an opening 28 at the rear end for admitting the spring 12. The said rear wall portion is composed of two parts in spaced relation in the form of bars that extend generally axially and in parallelism, the top bar 29 forming the upper limit or border of the housing and the bottom bar 30 constituting the lower limit or border thereof. The front wall portion consists of a plate-like bar 31 that extends longitudinally or axially across the space 32 between the bars 29 and 30, 85 and positioned about midway therebetween, and spaced laterally from the said bars. The opposed inner faces of the bar 31 on one side and of the two bars 29 and 30 on the other side serve as sliding bearing faces for the hammer member 11. The bar 31 shown as the front bar in Fig. 1 is at the left when in use and the rear bars 29 and 30 as referred to above is at the right. In the front end wall of the operating space 32 for the hammer member 11 is provided a notch 33 that serves as a fulcrum for the hammer member 11.

The hammer member 11 comprises a plate-like body portion that fits in the space 100 32 and extends generally vertically or transversely between the bar 31 on one side and the bars 29 and 30 on the other side, has on the rear edge portion a notch or recess 27, already mentioned, for the inner end 105 of the spring 12, and a finger 35 extending forwardly from the front edge portion that serves as the fulcrum for co-operating with the notch 33, and has on the lower edge portion an extension that projects downwardly 110 into the guard space, inclosed by the loop 16, and serves as the trigger, and has at the

upper end the handle or thumb-piece 37 at the rear and the nose 38 at the front.

The face 39 of the hammer 38 is tapered or wedge-shape, suitably to operate on different sized caps and the anvil 15 is correspondingly tapered, as is also the retaining flange 40 that overhangs the anvil 15, for retaining the caps in place.

The left bar 31 of the body 17 co-operates 10 with the adjacent portion of the web 25 of the handle 14 to retain the inner end portion of the spring 12 in the operative position. As described the spring 12 is positively held in position near the end 15 portions in such a manner that the body portion will lay along the web 25, and because of the manner in which the spring is held in all positions of use I am enabled to use round spring wire for making the same.

20 The spring 12 holds hammer member 11 engaged with its fulcrum, and operates to hold the same in either the cocked position or the fired position, the bars that form the side faces of the housing or body 17 serving 25 as lateral guide members therefor.

In the modification shown in Figs. 4 and 5 the barrel 13^a is a separate piece of cylindrical form, made of a piece of tubing, mounted on a lug 41 on the front end of 30 the frame structure 10^a.

Also, the body 17^a differs in detail from the body 17 shown in Figs. 1 and 2 as follows:

In the body 17 the front plate-like bar 31 35 is supported at both ends, the front end being connected with the solid portion 42 of the body, just below the anvil 15, and the rear end merging with the flange 19 of the handle 14 both at the upper side 43 of the 40 opening 28 for the spring 12 and at the lower side 44 thereof. In the construction shown in Figs. 4 and 5 the bar member 31^a 45 is of plate-like form and is supported from the front end 42^a only and the opening 28^a at the rear end is essentially an extension of the general interior space 32^a for the hammer member 11. In the style shown in Figs. 1 and 2 there are three outlets for the 50 space 32, one at the top for the hammer end of the hammer member 11, one at the bottom for the trigger 36, and one at the rear, designated as 28, for the spring 12. In the style shown in Figs. 4 and 5 there is only one opening, 32^a, and the plate or bar member 31^a overhangs the said space sufficiently to serve as the guide and positioning 55 means for the hammer member 11 and the spring 12. The upper bar 29^a is straight, as in Fig. 1. The lower bar 30^a has a curved 60 upper edge in continuation of the curved rear edge of the opening 28^a, the opposed edge 45 of the bar member 31^a being similarly curved, to correspond generally to the swinging movement of the hammer member 11 on its fulcrum.

In both styles of construction it will be noted that in guiding the hammer member the principle of the three point bearing is involved, in that on one side the guiding means consists of two guide bars in spaced 70 relation and on the other side the co-operating guiding means comprises a single bar that is positioned in opposition to the space between the said two guide bars.

Both the hammer member and the spring 75 serve as operatively moving elements, having a limited to and fro movement, and each is provided with lateral guiding means in the form of flat sliding surfaces that permit of such movement, and the said surfaces are 80 part of a unitary and integral structure.

I claim as my invention:

1. A toy-pistol comprising a body and a handle connected thereto, a hammer member fulcrumed in the said body, a spring extending along the said handle, having one end portion projecting into the said body and engaged with the said hammer member, sliding contact surfaces being provided for engaging with parts of the lateral edges of the 90 said end portion, positioned adjacent the junction of the said body and handle, and in off-set relation, whereby one contact surface is engaged with the lateral edge of one part of the said spring and the other contact surface is engaged with the lateral edge of another part thereof.

2. In a toy-pistol, a frame structure for operatively housing a hammer member and a spring, and the said structure comprising 10 in a unitary piece, means for receiving the said hammer member and spring, an anvil, and a trigger guard in the form of a loop and co-operating fulcrums on the said hammer member and frame, the said means comprising guide-wall portions on both sides of the said hammer member and spring.

3. In a toy-pistol, a frame structure, a hammer member and a spring housed in the said structure, a trigger guard on the said 1 structure, the said structure having integral means for retaining the said hammer member in position for co-operating with the said spring and the said means being of skeleton form, operative as guide surfaces 1 in engagement with the side face portions of the said hammer member, the surface on one side being engaged with one part of the said hammer member, and the surface on the other side being engaged with a different 1 part thereof.

4. In a toy-pistol, a frame structure, a hammer member and a spring housed in the said structure, a trigger guard on the said structure, and the said structure comprising a unitary piece of material provided with integral means for retaining the said spring in position for co-operating with the said hammer member in the form of a plurality of guide surfaces engaged by the lat- 1

eral edges of parts of the said spring, the parts that are so engaged on one side being different from the parts on the other side.

5. In a toy-pistol, a frame structure having an anvil and a guard, a hammer member and a spring, and the said structure comprising a unitary piece of material provided with integral means for retaining the said hammer member and spring in position for 10 coöperating one with the other, the said means being in the form of guide surfaces on opposite sides of the said hammer member and spring, and the guide surface on one side being opposed to an open space on the 15 other side.

6. In a toy-pistol, a body for housing a hammer member, a handle member connected to the said body, a spring extending along the said handle member and having 20 one end projecting into the said body for engaging with the said hammer member, and the said handle member having an outstanding lug on one side face adjacent the other end of the said spring for holding the 25 said other end of the spring in operative

position, with the body portion thereof extended along the said side face.

7. In a toy-pistol, a body, a hammer member housed in the said body and having a fulcrum projection engaged with the end 30 wall of the said body, the said body having lateral guide members for coöperating with the said hammer member, and the said guide members comprising on one side a pair of guide bar members in spaced relation and 35 on the other side a guide bar member that is positioned opposite the space between the said pair of guide bar members.

8. In a toy-pistol, a frame structure, a moving element housed in the said frame 40 structure and having a limited to and fro movement therein, and the said frame structure consisting of a unitary, integral structure having a plurality of flat sliding surfaces that are engaged with the lateral 45 edges of the moving element.

CHARLES ALEXANDER BAILEY.
